UNITED STATES PATENT OFFICE.

FRANK J. FRIESE AND JOHN E. GILBERT, OF ST. LOUIS, MISSOURI, ASSIGNEES OF TWO-THIRDS TO EDWARD A. MORE, OF ST. LOUIS, MISSOURI.

MOLD FOR BRASS JOURNAL-BEARINGS.

SPECIFICATION forming part of Letters Patent No. 726,523, dated April 28, 1903.

Application filed November 3, 1902. Serial No. 129,815. (No model.)

To all whom it may concern:

Be it known that we, FRANK J. FRIESE and JOHN E. GILBERT, citizens of the United States, residing in the city of St. Louis, in the 5 State of Missouri, have invented certain new and useful Improvements in Molds for Making Railroad Car and Engine Brass Journal-Bearings, of which the following is a full, clear, and exact description, reference being 10 had to the accompanying drawings, forming part of this specification.

Our invention relates to a mold particularly suitable for use in making railroad car and engine journal-bearings or "brasses;" 15 and it consists in features of novelty herein-after fully described, and pointed out in the claims.

Figure I is a perspective view of our mold closed. Fig. II is a horizontal cross-section 20 taken on line II II, Fig. I. Fig. III is a vertical transverse section taken on line III III, Fig. II. Fig. IV is an elevation of the mold open and looking at the inside faces of the members. Fig. V is a perspective view of the 25 pin used in dislodging the casting from the mold. Fig. VI is a perspective view of the clamp by which the members of the mold are held in closed position.

1 designates the drag of the mold, which is 30 provided with a flanged base 2, by which it may be fixed upon a suitable support and held.

3 designates the cope of the mold, which is connected to the drag by a hinge-pin 4, which 35 passes through ears carried by the drag and cope and connects the cope to the drag in such manner that it may be swung to the drag to close the mold or swung away from it to open the mold. The drag and cope 40 members of the mold each have tapering side faces 5 at the opening edge of the mold.

6 is a U-shaped clamp provided with a handle 7 and having interior beveled faces 8. (See Fig. VI.) This clamp is adapted to be 45 applied to the mold, as shown by dotted lines, Fig. II, so that it will embrace the tapering faces 5 and when driven onto the mold will hold the drag and cope firmly together during the molding operation. After the casting has

been produced the clamp is readily disengaged by striking it a blow with a hammer to permit the opening of the mold.

9 designates lugs projecting from the forward edges of the drag and cope and provided with opposing inclined faces 10, between 55 which a pryer or wedge may be introduced to force the lugs apart and swing the cope away from the drag.

11 designates a pin loosely mounted in the drag 1 and provided at its inner end with a 60 head 12. This pin normally projects beyond the outer face of the drag and is adapted to be struck to drive it inwardly through the drag after the casting has been produced for the purpose of dislodging the casting.

13 designates a marking-plate removably mounted in the cope 3, so as to occupy a position in the mold-chamber and occasion the imprint of characters thereon in the casting produced: The plate is held by screws 14. 65 70

15 designates reinforcing-ribs on the outer side of the cope, which serve to strengthen that section of the mold.

17 designates the ingate of the mold, one half of which is contained by the drag 1, as 75 indicated at 17^a, Fig. IV, and the other half of which is contained by the cope 3, as indicated at 17^b, Fig. IV. The ingate leads to the bottom of the mold-chamber to convey the metal first introduced directly to 80 the bottom of the chamber, and 18 is a series of sprues leading at intervals from the portion 17^a of the ingate into the mold-chamber through which the metal flows to the chamber from the ingate as the chamber 85 is filled, thereby providing for the gradual filling of the chamber from the bottom upwardly, the metal flowing through the succeeding sprues from the ingate after the chamber below them has been filled and 90 avoiding the occurrence of chilled metal at the top of the mass of metal in the chamber that would occur in the event of the chamber being filled entirely at the bottom.

19 designates a large flow-gate situated in 95 the drag and cope at the top of the mold-chamber and adapted to provide full and ample vent from the chamber to permit ex-

pansion and contraction of the casting and avoid such shrinkage thereof as would render the casting liable to crack while cooling.

The mold herein described is constructed

5 entirely of metal, and by the described construction is rendered particularly adaptable for casting the journal-bearings of railroad cars and engines, such as are commonly known as "brasses," which it has heretofore been 10 found difficult to cast in metal molds, owing to their peculiar contour and irregular shape and thickness that renders them extremely liable to crack in cooling.

We claim as our invention—

15 1. The combination of a sectional mold provided with an ingate contained partially in one of its sections and partially in the

other and leading to the bottom of the mold-chamber, and a series of sprues leading from said ingate to the mold-chamber, substantially as set forth.

2. The combination of a sectional mold provided with an ingate contained partially in one of its sections and partially in the other and leading to the bottom of the mold-chamber, a series of sprues leading from said ingate to the mold-chamber, and a large flow-gate located at the top of the mold, substantially as set forth.

FRANK J. FRIESE.
JOHN E. GILBERT.
